UNITED STATES PATENT OFFICE

GLENN L. HILEMAN, OF DENVER, COLORADO

GAS BURNER

Application filed February 23, 1928. Serial No. 256,254.

This invention relates to a gas burner more particularly of the type designed to be installed through the ash door of a heating plant so as to convert coal burning heaters 5 into gas burners.

One of the principal difficulties encountered in burning gas is that if a sufficient amount of air is admitted with the gas for efficient combustion, the air and gas mixture 10 will ignite and backfire with an explosion. This same explosive effect occurs when the gas is turned off, for the air and gas mixture will burn down into the burner tube, and cause an explosion therein.

15 The principal object of this invention is to provide a gas burner which will quietly ignite or extinguish and yet which can handle a large amount of air so as to secure a short, high temperature flame.

20 Another object of the invention is to provide means for feeding auxiliary air directly to the combustion zone so as to effect a more complete combustion and a higher temperature flame.

25 Another object is to provide independent set regulations for both the auxiliary air and the main air and so arrange these set regulations that they will act dependently to automatically proportion the total air to the 30 total gas flow.

Still another object is to provide means for effectively supporting the main gas and air manifold within an auxiliary air manifold so that its position can be adjusted there- 35 in and so that combustion will take place within a surrounding sheet of fresh air.

A further object is to provide a burner tip 40 of special design which will not rapidly deteriorate from the intense heat of the flame and which can be quickly and easily replaced.

A still further object is to provide an igniter or pilot burner tip which will not be affected by the chemical action of the constantly burning pilot flame and in which the flame will be protected from extinguishing 45 drafts.

Other objects and advantages reside in the detail construction of the invention, which 50 is designed for simplicity, economy, and

efficiency. These will become more apparent from the following description.

In the following detailed description of the invention reference is had to the accompanying drawing which forms a part hereof. 55 Like numerals refer to like parts in all views of the drawing and throughout the description.

In the drawing:

Fig. 1 is a longitudinal section through 60 my improved burner taken on the line 1—1, Fig. 2.

Fig. 2 is a plan view thereof.

Fig. 3 is a front view of the complete apparatus.

Fig. 4 is a detail view of the stationary 65 face plate.

Fig. 5 is a detail section through the igniter or pilot burner taken on the line 5—5, Fig. 2.

The invention comprises a burner base 10 of fire clay or similar refractory heat resisting material. The base 10 is formed in segments to facilitate its installation through the doors of a furnace. In conversion installations the usual grate bars are removed and the burner base 10 is placed so that the top face will be on a level with the position formerly occupied by the top of the grate bars. The burner base 10 contains a tapered central opening which we will designate as the auxiliary air opening 11. This opening surrounds a burner tip 12 which is formed of some highly fire resistant refractory material and provided with a plurality of angularly placed flame orifices 13. The burner base 10 70 is supported upon a relatively large elbow casting 14 which connects with an auxiliary air pipe 15.

The outer extremity of the pipe 15 is secured in a regulator casting 16. Across the face 90 of the regulator casting 16 a fixed face plate, shown in detail in Fig. 4 and designated by the numeral 17, is secured. This face plate supports a Venturi tube or mixing chamber 18 within the auxiliary air pipe 15. The burner tip 12 is supported in a tip holder 19 carried from an elbow 20 on the mixing chamber 18. The tip 12 can be adjusted to a concentric position within the opening 11 by means of set screws 21 which pass through the pipe 15 into 95 100

contact with the mixing chamber 18. Gas is fed to the burner from a gas supply pipe 22 which passes concentrically through the face plate 17 terminating in a nozzle 23.

5 The total volume of air to the burner is controlled by means of a damper plate 24 which is rotatable about the gas supply pipe 22 and is maintained in contact with the face plate 17 by means of a set collar 38 upon the gas 10 pipe 22. The damper plate 24 is provided with an outer series of openings which correspond in number and spacing with a similar series of openings in the face plate 17 to admit air to the auxiliary air pipe 15. The 15 damper plate 24 is also provided with an inner series of openings arranged to register with a similar series of openings in the face plate to admit air to the mixing chamber 18.

The volume of auxiliary air which may pass 20 through the outer series of openings in the damper plate 24 is set by means of an annular auxiliary air plate 25 having corresponding series of openings therein. The volume of primary air which may pass through the inner series of openings in the damper plate to the mixing chamber 18 is controlled by means 25 of a circular primary air plate 26 having openings which register with the inner series of openings in the damper plate.

30 The auxiliary air plate 25 and the primary plate 26 may be both locked in any desired position upon the damper plate 24 by means of clamp nuts 27 which are carried on studs projecting from the damper plate. Thus when 35 the primary and auxiliary plates are locked in position they must always move with and as a part of the damper plate.

The damper plate is moved upon the face plate 17 by means of a lever 28 which projects therefrom. This lever is connected by means 40 of a link 29 to a lever 30 of a gas valve 31. The link 29 is connected to the lever 30 by means of a pin 32 in the lever adapted to travel in a slotted opening 33 in the link. The gas 45 valve lever 30 is raised or lowered by a cable or chain 34 from any manually or thermostatically controlled apparatus. A weight 35 is provided to return the damper plate to its closed position. The movement of the damper plate is limited by an arcuate slot 36 therein which rides over a pin 37 extending from the regulator 16 through the face plate 17.

50 Ignition of the burner is accomplished by means of a small pilot flame. Gas is supplied to this flame by means of a pilot tube 38 which extends upwardly into the burner block 10 terminating against a pilot tip 39. The pilot tip 39 is wedge-shaped and is forced into a similar wedge shaped hole in the base block 10. The pilot tube 38 is cemented into the base block against the bottom of the pilot tip 39 as shown at 40.

55 By this arrangement there is no metal in contact with the pilot flame and the flame is 60 protected by the base block from drafts. All

surfaces with which the flame contacts are of refractory material so that the trouble usually encountered with pilot tips is not present in this invention. Heretofore such tips have been of metal which the pilot flame quickly 70 corrodes and eats away.

Assuming the pilot flame is burning, to start the burner the lever 30 is raised. The first movement of the lever 30 opens the gas valve 31 allowing pure, unaerated gas to flow 75 through the mixing chamber and out of the burner openings 13. This gas is immediately ignited by the pilot flame, but since there is no appreciable air in the mixing chamber, the flame will not burn down therein and cause an explosion. It therefore ignites 80 quietly as a luminous flame.

Further movement of the lever 30 brings the pin 32 to the end of the slot 33, draws 85 upon the link 29 and rotates the damper plate 24, thus admitting air to the flame through both the mixing chamber and the surrounding auxiliary air passage. This air immediately changes the nature of the flame to a heating flame without explosion.

90 When it is desired to shut off the burner entirely, the lever 30 is lowered and the weight 35 immediately closes the damper plate 24 against the stop pin 37 so as to shut off all air to the flame. Gas is still flowing through 95 the mixing chamber however, and, when the air is shut off the flame changes back to the quiet luminous type, which may be quietly extinguished by entirely closing the gas valve 31. There is no explosion at the close because 100 at this time only pure gas is contained within the mixing chamber and no air is present for combustion purposes.

The burner should be regulated first by means of the primary plate 26 to obtain a 105 short, hot, flame. The auxiliary air is then regulated to supply all the air to the flame that it can conveniently use. The two plates should then be locked into position upon the damper plate after which, regardless of the 110 position of the damper plate, the proportional regulation will be correct.

115 It is easy to replace the burner tip 12 when necessary as it rests within a tapered cup-like depression in the tip holder 19, the taper of which insures a tight joint.

120 It is essential that the burner openings 13 open outwardly at an angle so as to intimately mingle the flames with the air from the auxiliary opening 11.

While a specific form of the improvement has been described and illustrated herein, it is desired to be understood that the same may be varied, within the scope of the appended claims, without departing from the spirit of 125 the invention.

Having thus described the invention, what I claim and desire secured by Letters Patent is:—

1. In a gas burner having a mixing cham- 130

- ber and an auxiliary air passage, means for controlling the air supply to both said mixing chamber and said air passage comprising, a face plate closing both said chamber and said passage and having openings communicating with each; a damper plate having corresponding openings movable on said face plate so as to control the openings therein; a first regulator plate having openings adapted to register with the openings in the damper plate which control the air to the air passage; a second regulator plate having openings adapted to register with the openings in the damper plate which control the air to the mixing chamber; means for locking both said first and second plates in any desired independent position upon said damper plate; and means for moving said damper plate upon said face plate so as to control all of said openings simultaneously. 10 15 20
2. A gas burner comprising an auxiliary air passage; a mixing chamber positioned within said air passage; a burner tip in communication with said mixing chamber; an air opening surrounding said burner tip in connection with said air passage; and means for controlling the air supply to said air passage and said mixing chamber both independently and simultaneously. 25 30
3. A gas burner comprising an auxiliary air passage; a mixing chamber positioned within said air passage; a burner tip in communication with said mixing chamber; an air opening surrounding said burner tip in communication with said air passage; and means for controlling the air supply to said air passage and said mixing chamber both independently and simultaneously, said means comprising a fixed plate having openings 35 40 45 communicating with both said passage and said chamber; a movable plate adapted to control all of said openings simultaneously, and adjustable plates carried by said movable plate and adapted to control certain of said openings independently. 50 55
4. A gas burner comprising a base block of refractory material having a tapered opening therethrough; an auxiliary air passage communicating with said opening; a mixing chamber; a burner tip positioned within said opening; a passage communicating between said mixing chamber and said burner tip; and a face plate supporting said mixing chamber within said auxiliary air passage, 60 65 said face plate having air openings. 70 75
5. A gas burner comprising a base block of refractory material having a tapered opening therethrough; an auxiliary air passage communicating with said opening; a mixing chamber; a burner tip positioned within said opening; a passage communicating between said mixing chamber and said burner tip; and a perforated face plate supporting said mixing chamber within said auxiliary air passage, and adjustable means for position- 80 85 90 95 100 105 110 115 120 125 130

ing said mixing chamber therein so as to control the position of said burner tip.

6. A gas burner comprising a base block of refractory material having a tapered opening therethrough; an auxiliary passage communicating with said opening; a mixing chamber; a burner tip positioned within said opening, said burner tip having a tapered bottom; a cup-shaped member adapted to receive said bottom and a passage communicating between said cup-shaped member and said mixing chamber. 70 75

In testimony whereof, I affix my signature.
